[57] CLAIM

The ornamental design for a packaging cup with a pedestal base, as shown and described.

DESCRIPTION

FIG. 1 is a side elevation view of a packaging cup with a pedestal base showing my new design, the view from each side taken at 90° intervals being identical;

FIG. 2 is a top plan view; and,

FIG. 3 is a bottom plan view thereof.

FIG. 1

FIG. 2

FIG. 3
